INVENTOR

UNITED STATES PATENT OFFICE.

BENJAMIN HOWE, OF LOUISVILLE, KENTUCKY, ASSIGNOR TO INTERNATIONAL TRADING COMPANY, A CORPORATION OF DELAWARE.

DESIGN FOR A LABEL OR SIMILAR ARTICLE.

48,687.

Specification for Design.

Patented Mar. 7, 1916.

Application filed June 28, 1915. Serial No. 36,900. Term of patent 3½ years.

To all whom it may concern:

Be it known that I, BENJAMIN HOWE, a citizen of the United States, residing at No. 1548 Cherokee road, in the city of Louisville, county of Jefferson, and State of Kentucky, having invented a new, original, and ornamental Design for Labels or Similar Articles, as shown in the drawing submitted herewith, and of which the following is a description, consisting of a vertical view of a bee with outstretched wings, the wings containing an outline sketch of the Eastern and the Western Hemispheres, the bee surrounded by an oval-shaped ornamental border and four circles representing, respectively, a miner, a mechanic, a farmer, and a home, with lines and arrow points between the circles, illustrating the idea that the products of the miner, the mechanic, and the farmer are carried from each to the others and from all to the home.

In the center of the design is shown a ver-

tical view of a bee, with outstretched wings, on the right wing is an outline sketch of the Eastern Hemisphere, while the Western Hemisphere is so sketched on the left wing; surrounding the bee is an oval shaped ornamental border, interrupted at four points by circles inclosing a representation of a miner, a mechanic, a farmer and a home, each of the circles diametrically or diagonally positioned in relation to the others.

Lines with arrow points are placed between the circles illustrating the idea that the products of the miner, the mechanic and the farmer are carried from each to the others and from all to the home.

I claim:—

The ornamental design for a label or similar article as shown and described.

BEN. HOWE.
